UNITED STATES PATENT OFFICE.

IGNACIO ARTEAGA, OF SAN ANTONIO, TEXAS.

RAILWAY SWITCH.

1,408,333.

Specification of Letters Patent. Patented Feb. 28, 1922.

Application filed May 25, 1921. Serial No. 472,432.

To all whom it may concern:

Be it known that I, IGNACIO ARTEAGA, a citizen of Mexico, residing at San Antonio, in the county of Bexar and State of Texas, 5 have invented certain new and useful Improvements in Railway Switches, of which the following is a specification.

This invention relates to that class of railway switch devices wherein the switch is 10 operative by the motorman or engineer without leaving his platform or cab, and has for one of its objects to improve the construction and increase the efficiency and utility of devices of this character.

15 Another object of the invention is to provide a device of this character which may be adapted without structural change to switches of various forms and sizes, and to trolley lines, or steam roads.

20 Another object of the invention is to provide a device of this character which is adapted without structural change to be operated by the foot of the motorman, when installed in connection with trolley lines, or 25 adapted to be operated by compressed air when installed upon trains equipped with air brakes.

With these and other objects in view the invention consists in certain novel features 30 of construction as hereinafter shown and described, and then specifically pointed out in the claims, and in the drawings illustrative of the preferred embodiment of the invention.

35 Figure 1 is a plan view of a portion of a conventional railway line with the improvement applied.

Fig. 2 is an enlarged detail in section on the line 2—2 of Fig. 1.

40 Fig. 3 is an enlarged detail in section on the line 3—3 of Fig. 1.

Fig. 4 is an enlarged sectional detail on the line 4—4 of Fig. 3.

45 Fig. 5 is a side elevation, partly in section, of a portion of a conventional trolley car including a part of the motorman's platform and a section of the track, with a portion of the mechanism applied.

Fig. 6 is a front elevation of the parts 50 shown in Fig. 5 with the platform and tracks in section on the line 6—6 of Fig. 5.

Fig. 7 is an enlarged detail illustrating the operation of the tripping mechanism.

55 Fig. 8 represents a modification in the construction to illustrate the manner of utilizing a part of the compressed air from

the air brake system when the device is installed on cars using air brakes.

Fig. 9 is a section enlarged on the line 60 9—9 of Fig. 8.

The improved apparatus may be installed in connection with trolley lines of the ordinary construction, or to the split switches of steam roads, but for the purpose of illustration is shown applied to an ordinary trolley 65 line in which 10—11 represents the main line rails 12—13 the siding or switch rails, 14—15 the "frog" portions, and 16 the switch "point" the latter pivoted at one end to the "frog" member 15 as shown at 17, and reduced at the free end to engage in a relatively long recess 18 in the inner face of the curved rail portion of the frog member. These parts are of the usual construction.

70 The ties are represented at 19, and mounted for rotation through certain of the ties is a shaft 20 having a crank plate 21 at one end and a gear 22 at the other end.

Attached to one face of one of the ties 19 at a suitable distance from the switch point 80 16 are spaced keepers 27, and slidable through these keepers is a bar 28 having gear teeth 29 in its lower face in constant engagement with the gear 22 and with lateral projections 30 at the ends, the outer 85 faces of the projections being reversely bevelled, as represented in Figs. 1 and 7.

A portion of a conventional trolley car body is represented at 31, with a portion of the motorman's platform at 32 and one of 90 the trucks at 33 mounted on the tracks 10 and 11.

Attached to the frame of the truck 33 at each side are guide brackets 34, and supported for vertical movement through each 95 bracket is a standard 35, each standard having a head 36 and a spring 37 operating to maintain the standard yieldably in its upper position.

At its lower end each of the standards 35 100 is provided with an enlargement 38 having bearing roller 39 and a downwardly projecting lug 40, the lugs having reversely inclined or bevelled confronting faces to engage the bevelled face 30 of the bar 28 as 105 hereafter explained.

The rollers are adapted to bear upon the head or tread portion of the rail and the projections 40 extend below the lower line 110 of the rollers when the standards 35 are depressed against the resistance of the springs 37.

When the improved apparatus is employed in connection with ordinary trolley lines, or those without air brake devices, the arrangement shown in Figs. 5 and 6 will be employed for actuating the member 28, and when employed in connection with lines having air brakes, the arrangement shown in Fig. 8 will be employed.

The arrangement shown in Figs. 5 and 6 10 comprises brackets or hangers 41 attached to the lower face of the platform 32, one near each side and each carries a stub shaft 42 on one end of which a small gear 43 is mounted and a grooved cable pulley 44 on the other end.

Attached to each of the brackets 34 are cable guide sheaves 45, one at each side, and attached at one end to each of the pulleys 44 is a pull cable 46, the latter being 20 divided as it approaches the sheaves 45 and passed thence over the sheaves to the head member 36 of the standards 35.

Slidable through the platform 32 are operating rods 47, one for each of the gears 25 43, and preferably square or other form than round to prevent them from rotating and each with a head 48 to be engaged by the foot of the motorman. Each rod 47 is enlarged below the platform and provided 30 with a spring 49 means to maintain the rod yieldably in upper position with the enlarged portion against the lower face of the platform. The enlarged portions of the rods 47 are each formed with gear teeth in constant engagement respectively with the pinions 43.

By this arrangement it is obvious that either one of the rods 35 may be depressed at the will of the motorman, to dispose either 40 one of the bevelled projections 40 into the paths of the bevelled faces 30 of the member 28.

With a car equipped as shown in Figs. 5 and 6, when approaching a switch, if the 45 "point" 16 is set for the main line and the car is to pass along the main line no attention is paid to the operating mechanism. If however, the car is to pass to the siding or switch track, and the "point" 16 is set for the main line, as shown in Fig. 1, the motorman depresses the rod 47 at the left and thus correspondingly depresses the rod 35 at the left through the action of the pull cable 46 at the left, and causes the roller 39 at 50 the left to engage the ball of the rail 11 and the bevelled projection 40 associated therewith to extend into the path of the bevelled projection 30 of the member 28 and throw the latter over to the right and cause the rack 29 to engage the gear 22 and oscillate the shaft 20 and thus cause the rods 24 and 26 to move the switch point into open position and guide the car upon the siding or switch track.

If the switch point 16 is "open" the member 28 will be disposed with the bevelled member 30 adjacent the rail 10 and if an approaching car is to continue along the main line, the motorman depresses the operating rod 47 at the right and thus closes the switch point by causing the projection 40 at the right to engage the bevelled projection 30 at the right end of the member 28 to reverse the motion of the shaft 20 and correspondingly reverse the motion of the members 24 and 26 and throw the switch point into closed position, as will be obvious.

Thus the motorman can throw the switch point in either direction without leaving his platform.

If the car is provided with air brakes the construction shown in Fig. 8 will be employed whereby a portion of the compressed air of the brake system will be utilized to operate the members 35 and their attachments.

In the modified construction the mechanism attached to the platform 32 and the guide sheaves 45 will be dispensed with and the head member 36 changed into piston 90 head form as shown at 50; in Figure 8.

The bracket 34 is likewise changed in form as shown at 51 and arranged to support an air cylinder 52 in which the piston head 50 operates. The members 35, 38, 39 95 and 40 are the same in the modified structure and operate in the same manner.

Two of the cylinders 52 and their attachments will be employed, one at each side, corresponding to the foot actuated devices 100 shown in Fig. 6, but one set only is shown for illustration.

Located upon the platform 32 are valve devices one of which is indicated at 53, and each preferably provided with an operating 105 rod 54 extending to a point convenient to the hand of the motorman and provided with an operating handle 55.

An air conductor tube 56 from the compressed air cylinder of the air brake system, 110 not shown, leads into the valve casing 53 while another air conductor tube 57 leads from the valve casing 53 to the cylinder 52.

The valve members 53 are preferably of the three way form, as shown in Fig. 9, so 115 that the air may be readily exhausted from the cylinder 52 after the operation of the mechanism, to permit the spring 37 to automatically return the member 40 to the initial or inoperative position.

By this arrangement the motor man may depress either one of the members 35 and produce the same results as when the mechanism shown in Figs. 5 and 6 is employed.

The improved device is simple in construction, can be inexpensively applied and modified to suit the various forms of ties.

The preferred embodiment of the inven-

tion is disclosed in the drawings and set forth in the specification, but it will be understood that any modifications within the scope of the claimed invention may be 5 made in the construction without departing from the principle of the invention or sacrificing any of its advantages.

- Having thus described the invention what is claimed is:—
- 10 1. In a railway switch operating device a standard adapted to be supported for vertical movement relative to a car truck, a spring holding said standard in elevated position, a shoe member carried by said stand- 15 ard and including a projection having an inclined face and a seat for a guide roller, said projection extending below the line of the ball of the rail on which the truck travels when in one position to engage a 20 switch point actuating mechanism, and the roller to engage the ball of the rail and limit the downward movement of the standard, and means under the control of the driver of

the car to depress said standard against the resistance of said spring. 25

2. A railway switch operating mechanism comprising a bracket device adapted to be attached to a car truck, a standard movable through said bracket, a spring operating to maintain said standard yieldably in elevated 30 position, a shoe member at the lower end of the standard and including a downwardly directed projection having an inclined face and a seat to receive a bearing roller, said projection extending below the line of the 35 ball of the rail on which the truck travels, when in one position and adapted to engage a switch point actuating mechanism, and the roller to engage the ball of the rail and limit the downward movement of the stand- 40 ard, and means under the control of the driver of the car to depress said standard against the resistance of said spring.

In testimony whereof, I affix my signature hereto.

IGNACIO ARTEAGA.
